UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPE-BAR MACHINE.

No. 919,240.

Specification of Letters Patent.

Patented April 20, 1909.

Application filed April 19, 1901, Serial No. 56,636. Renewed March 10, 1909. Serial No. 482,573.

To all whom it may concern:

Be it known that I, FRANCIS H. RICHARDS, a citizen of the United States, residing at Hartford, in the county of Hartford and State of Connecticut, have invented certain new and useful Improvements in Type-Bar Machines, of which the following is a specification.

This invention relates to mechanism for 10 making a wrought or forged type and for making a succession of the same on a blank to form a line of type.

There is described and claimed in an application—Serial No. 79,359, filed by me on 15 the 21st day of October, 1901, and co-pending with the present application, certain improvements in methods of forming wrought types upon the edge of a proper blank, which improvements, briefly stated, involve 20 the impartation of a relative subsidiary movement to the type-making members (that is, the blank and the type-forming die) which operates in conjunction with the ordinary feeding or compressing movement 25 of the one member against the other to facilitate the production of a complete and satisfactorily formed type. As instances of such relative subsidiary movement, there is specified in the application referred to, a 30 simple oscillatory movement from side to side either about an axis or else this movement results in a motion of one of the members in relation to the other along a cycloidal path similar to that traced by a 35 point in a circle as it rolls to and fro over a surface either straight or curved—the geometrical path traced by the member lying at and adjacent to the cusp of the cycloid. As a result of these combined motions— 40 that is, a motion to compress the die against the blank, and a relative oscillatory motion, the surplus material is rolled sidewise beyond the edge of the blank and the type is formed gradually and by a progressive operation, as fully set forth in the specification 45 forming part of the aforementioned application. When such subsidiary movement takes place about a definite axis, and this axis extends longitudinally of the 50 blank, and is located in or adjacent to the impression face of the completed type, there is, evidently, during a portion of the type-forming operation, a slight to-and-fro lateral movement of the extreme edge of the 55 blank which is under the compression of the

die, since the common level of the upper or impression face of the type is somewhat below that edge. Such lateral motion, however, naturally decreases in extent as the die advances into the blank and approaches the 60 axis of oscillation. That is to say, during a portion, at least, of the period in which a type is being formed, there is a sidewise movement of the upper edge of the blank and a co-incident, but greater, movement of 65 the lower edge thereof, this motion in the instances referred to, resulting from a simple motion about an axis or a back and forth rolling movement. Such motion, however, may be attained as a result of compounding devices motions imparted to the blank, and the present invention relates to 70 mechanism adapted to simulate this motion as well as to produce an oscillation of the axis of oscillation besides other modified 75 motions as a result of imparting to one edge of the blank an oscillatory motion and to the other edge a similar motion, but independent of the first, whereby the point or surface of application of the die to the mass 80 within the die is constantly changing.

In the drawings accompanying the present specification Figure 1 is an end elevation of a mechanism embodying my present improvements. Fig. 2 is a plan view thereof. Fig. 3 is a side elevation of the mechanism, certain portions being broken away in this figure, while certain other portions are shown in section. Fig. 4 is partly a plan and partly a sectional view thereof, the plane of the section being indicated by the dotted line 4—4 in Fig. 1, and the mechanism being viewed in the direction of the arrow adjacent to that line. Fig. 5 is a sectional elevation on the plane of the dotted line 5—5, in Fig. 2, looking in the direction of the arrow, adjacent to that line. Fig. 6 is a perspective view of a clutch member embodied in the mechanism. Fig. 7 is a side elevation of the main driving shaft 100 showing the various cams thereon and a certain clutch device for controlling the motion thereof. Figs. 8, 9, 10, and 11 are elevational views of the various cams shown in Fig. 7, the cams being removed from their 105 positions on the shaft in the latter figure. Figs. 12, 13, and 14 are diagrammatic views, illustrating the movement of the blank during the type-forming operation. Fig. 15 is 111 a perspective view of the carriage and vari-

ous supporting members employed in the illustrated machine for maintaining the blank in position and rocking it and the supports of the blank-holder, the latter it-
5 self not being shown in this figure, while certain members are omitted and others are broken away. Fig. 16 is a perspective view of the blank-holder. Fig. 17 is a similar view of the rock frame on which the blank
10 holder is pivotally supported; and Fig. 18 is likewise a perspective view of one of the actuatable wedges serving to feed the blank in the blank-holder against the dies.

Similar characters of reference designate
15 corresponding parts in all figures.

The supporting frame may be of any suitable form and construction, appropriately comprising a main frame provided with subordinate frame parts or elements for
20 maintaining in place the various operative parts of the mechanism. In the present embodiment this frame comprises a bed-plate, designated in a general way by B, supported upon suitable legs b.

25 As the present invention relates particularly to a mechanism whereby a back-and-forth movement of the axis of oscillation of the aforementioned subsidiary motion about an axis as well as other relative motions of
30 a different nature may be effected through the conjoint and combined action of separate motions, certain of the instrumentalities involved in the making of a type and a type-bar are represented in a conventional way,
35 and the particular representation is not, therefore, designed to limit in any way the application of the present improvements. For instance, the various type-forming dies
40 may be brought to the type-forming point in some suitable manner and by some suitable means, such, as an instance of an appropriate mechanism, being set forth in my applications copending with the present one. For the purposes of the present illustration,
45 however, I have shown a number of dies, each die being designated in a general way by D, which are adapted to be brought to the type-forming point by hand. That is to say, a die, after its selection, may be ad-
50 justed from a point in which it normally is out of its type-forming position to a point where it is adapted to be pressed against the edge of a proper blank. These dies D are conveniently mounted upon a carrier C,
55 which, in the present instance, is shown as a rotary carrier or disk, whose shaft 2 is mounted in bearings provided in or supported by uprights 4 and 4'. The dies may also be of any suitable construction, pro-
60 vided with accessory parts if desired, or the same may be destitute thereof agreeably to the particular mode of action, which it is designed that the die shall have during the type-forming operation. A hand wheel 5 is
65 provided in the present organization for the

convenient manipulation of the die carrier; and I have also shown means for insuring the correct positioning of a selected die with reference to the type-forming point, this means operating to lock the die carrier in its
70 adjusted position. A locking pin 6 adapted to move longitudinally in the bore of a recess provided in a projection 7 of the up-
right 4, is surrounded by a spring 8 inserted between a collar 8' attached to the pin and a plug or fixture 8", and operating to thrust the pin in the direction of the die-carrier. A finger piece 9 secured to the outer end of the pin enables the latter to be drawn away from the carrier, whereupon the carrier may
75 be adjusted and the released pin permitted to enter one of a number of openings 10, provided in the carrier and corresponding to the various dies, the pin having a shoulder 8³ to limit its movement. These openings
80 may have arranged adjacent to them various characters, which are so related to the dies, that when a particular opening is opposite the pin, the corresponding die is properly located at the type-forming point.
85

I have shown in the present instance a blank-holder designated in a general way by E, adapted to receive and support a length of typebar-blank and to feed the same lengthwise to bring successive portions under the die-carrier. As herein constructed this blank or work-holder consists of an elongated block formed with a longitudinal slot 11 in which a blank, designated in a general way by H, may be secured by suitable means—screws 11', 11' being in this instance provided for the purpose.
90

It has already been stated that the oscillatory motion imparted to the blank in practicing the present invention, is crosswise of the blank and for the purpose of enabling this motion to be given to the latter the work-holder E in the present embodiment is provided at its ends with pivotal members 12 and 12 defining the main axis of oscillation of the blank-holder, which axis is preferably located immediately adjacent to the impression face of the types of the finished typebar.
100

A particular feature of the present invention consists in an axis of oscillation of the blank which is in itself susceptible of an oscillatory movement from side to side coincidently with the occurrence of the oscillation about said axis whereby the point of application of the working die is continually shifted and the forging and other actions accentuated. To enable this oscillatory movement of the main axis of oscillation to be effected, in the construction embodied in the present application of the invention, these pivotal members 12 and 12 are journaled in supports 13 and 13, respectively, forming part of an oscillatory frame, designated by F, which in the par-
110
115
120
125
130

ticular instance illustrated comprises a rock shaft *f* defining the axis of oscillation of the frame and hence of the frame components 13, 13. This construction enables an oscillatory or vibratory movement to be imparted to the oscillatory axis of the work-holder through suitable mechanism, a form of which will be hereinafter described. A section *f'* of a tube encircles the shaft *f* and 10 serves to locate the supports 13, 13 at the correct distances apart, it being understood that these supports are fastened to the rock shaft.

To facilitate the movement of the work-holder and the contained blank toward the type-forming die, the pivotal bearings for the ends of the rock shaft *f* of the frame *F* are conveniently located in sliding members 14, 14, which are mounted in suitable guide- 20 ways to permit of their motion toward and away from the die-carrier.

From what has already been stated, it is evident, that the blank-holder must be adapted to have a longitudinal motion imparted to it to bring successive portions of the blank contained in the holder under the die-carrier. As organized in the present instance and for the convenient attainment of this feeding movement, the guideways 30 for the members 14 and 14 are formed in uprights 15 and 15, extending from a carriage designated in a general way by *G*, which is mounted in a guide recess provided in the bed-plate *B* where it is retained 35 and confined to its rectilinear movement by gibs 16 and 16.

Some suitable device is employed for moving the work-holder and its various associated parts toward the die-carrier, there 40 being shown in the present drawings a device for this purpose, embodying a pair of slides 17 and 17, mounted to move transversely to the direction of the feeding movement of the carriage in suitable guideways 45 therein. Each slide 17 is provided with an inclined portion 17' entering a correspondingly inclined recess in the corresponding member 14. Evidently, a motion of the slides back and forth will impart to the 50 members 14 and 14, and consequently to the work-holder, a motion toward and away from the die-carrier and as a means for causing this to-and-fro movement of the slides each slide is provided with a rack 55 portion 18, whose teeth engage with the teeth of a corresponding pinion 19, both of which pinions are secured to a shaft 20, journaled in uprights 20', 20' upon the carriage. This shaft 20 extends longitudinally 60 of the blank-holder and there is, in the present instance, provided for its actuation a cam 21 adapted to actuate the shaft through a link 22, provided with a cam or antifriction roller 23, bearing against the 65 cam and with the periphery of which it is

held in contact by a spring 24. This link 22 at its upper end is pivoted to an arm 24' whose hub 24" encircles the shaft 20, but is mounted on the shaft to permit of the longitudinal movement of the latter, motion 70 being imparted through a pin (not shown) extending from the hub and entering a longitudinal slot or keyway 20² in the shaft. As shown, particularly in Fig. 3, the shaft enters an upright 25 and also passes through 75 the aforementioned upright 4' in which uprights the shaft is journaled, the uprights operating to prevent the movement of the hub 24" in the direction of the shaft. The link 22 may be slotted at its lower end and 80 embrace the shaft to which the cam 21 is secured, thus affording a guide for controlling the lower end of the link.

The main driving-shaft *S* is mounted in suitable bearings *s*, *s'* and provided with an 85 appropriate driving-pulley *S'* by which the shaft may be rotated from any convenient source of power this pulley being illustrative of one means for effecting the motion of the shaft. While it is intended that the pulley shall rotate continuously during the working of the machine, it is contemplated as the present machine is organized, that that portion of the main driving-shaft serving to actuate certain operative portions of 90 the machine shall not rotate except when caused or permitted to do so by the operator. To enable this particular mode of operation to be brought about the shaft and pulley 95 may be connected together by some suitable 100 device, for instance, a clutch, a form of which is herein shown comprising a pin 26 projecting laterally from an arm 27 fixedly connected with the driving-pulley *S'* and adapted to engage with which is an arm 28 105 mounted upon the main driving-shaft *S* to rotate therewith but being susceptible of a movement in the line thereof. This movement is in the present case a swinging movement about a pivot-pin 29 provided on a 110 flange-like collar 29' secured to the driving-shaft; a spring 30 bearing against the arm 28 tends to move the latter on its pivot and thrust the same into the path of motion of the pin 26. Normally, however, the arm 28 115 is held out of the path of motion of the pin and against the tension of the spring by a locking-lever 31 fulcrumed, see 32, to the bed-plate *B*, or a fixture thereof, and provided at its lower end with a hook-shaped 120 portion 33 into which the arm 28 fits. When this locking-lever is moved upon its pivot by the operator through the medium of a suitable hand-lever, designated in a general way by *L*, and connected by a link 34 with 125 the locking-lever, the hook-portion 33 is withdrawn from engagement with the arm 28 and the latter under the action of spring 30 is thrown forward into the path of motion of pin 26. Further rotation of the 130

main driving-pulley now effects the rotation of the main driving-shaft in a manner evident from the foregoing described construction. As organized in the present instance 5 the proper operation of the mechanism requires the swinging back of locking-lever 31 into the position from which it was withdrawn to start the motion of the driving-shaft, before the completion of the rotation

10 of the driving-pulley. When this has been done the arm 28, as it nears the end of its full revolution about the axis of the main driving-shaft, contacts with an inclined or cam-shaped portion (see 35) on the locking-lever 31 and further movement of the driving-pulley serves to withdraw the arm from engagement with the pin 26 thus freeing the driving-shaft from the driving-pulley which latter may then continue its rotation idly.

15 20 Referring now to the means provided by the present construction for effecting the oscillation of the work-holder and its associated parts about the two axes of oscillation, as previously described, 36 designates an oscillator-shaft for effecting oscillation about the pivoted portions 12, 12, and 37, a corresponding shaft for effecting the oscillation about the pivotal portions 14 and 14.

The best results follow, I find, from an oscillation of a comparatively rapid character 30 and to enable a desired rapidity of oscillation to be derived independently of the speed at which the main driving-shaft rotates, there is provided a separate driving-shaft, 35 designated in a general way by 38, for imparting motion to the two oscillator shafts. This shaft 38 as well as the oscillator shafts, are mounted in suitable bearings supported in this instance upon the uprights 4 and 4', and the former shaft is provided 40 with a suitable driver, for example a driving-pulley 39 driven from any convenient source of power. Motion is communicated from the driving-shaft 38 to the oscillator 45 shaft 36, in the present construction, by a crank-pin 40 extending from a crank-disk 41 secured to the driving-shaft 38 and connected by a link 42 with an arm 43 extending from the said oscillator-shaft. The oscillator-shaft 36 acts as a driver for the oscillator-shaft 37, the connecting means herein shown consisting of a link 44 pivoted to arms 45 and 45' extending, respectively, from the oscillator-shafts.

50 55 I have found the best results to follow by varying the extent or amplitude of the oscillatory movement imparted to the work-holder during the period of forming the type, such oscillation decreasing in the preferred mode of operation, during the later stages of such period and for the purpose of enabling this variation to be accomplished automatically during the operation of the mechanism, about both axes of oscillation as well as to enable the oscillation to

be reduced to zero, corresponding to the beginning and the ending of the type-making operation, I have provided in the present construction means for imparting oscillation to the blank which enables and causes 70 the throw of the oscillator-shafts to vary from zero to a maximum and conversely, whereby, when the throw becomes zero, no oscillatory movement will be imparted to the work-holder, even though the oscillator-shafts be in constant motion. That is to say, to the oscillator-shaft 36 is attached a guide member 46 lengthwise of which and transverse to the axis of the shaft is adapted to slide a block 47 from a position 80 in which the pivotal axis of a link 48, which is pivoted thereto and transmits its motion to the blank-holder coincides with the axis of oscillation of the guide member to a position in which it does not so coincide. 85 Similarly, the oscillator-shaft 37 is provided with a guide member 49 whose guide surface extends transversely to the axis of the shaft and along which is adapted to move a slide block 50. This guide member 49 is shown, 90 particularly in Fig. 2, to be box-like in form, a web 49' being provided for connecting the portions of the shaft on opposite sides of the member and strengthening the structure. The link 48, already mentioned, 95 is pivotally connected with the blank-holder F and to enable the latter to have a free lengthwise feeding movement this connection embraces a rod 51 secured to extensions 51', 51' of the holder and to which the link 10 is connected, the latter being confined to the plane of its vibration by the vertical side faces of a slot formed in a boss 52 extending from the upright 4. As herein constructed the oscillator-shaft 37 imparts its 1 motion to the main axis of oscillation of the work-holder by means of a rock-arm 53 fulcrumed to and held in position by a collar 53' on the shaft 2 and a link 54, the arm being extended in the direction of the longitudinal feeding movement of the blank-holder to engage with a notch 13' formed in an extension of one of the supports 13 constituting a part of the oscillatory frame F, whatever be the position assumed by the 1 holder during its longitudinal feeding movement.

It is evident from what has already been said that the oscillatory movement begins from a state of rest, and after passing through its various phases is suppressed at or some time before in point of time to the completion of a type and as constructed herein, these results are accomplished by shifting the said sliding-blocks and thus varying their throw to correspond with the desired relation and character of the oscillatory movements by means of suitable actuators on the main driving-shaft S, the construction embodying a link 55 pivoted to the

link 48 and movable in a lengthwise direction from an actuator in the form of a cam 56 upon the main driving-shaft which bears against a cam or antifriction-roller 57 on the link. Similarly, a link 58 pivoted to the link 54 is shiftable from a cam-like actuator 59 on the driving-shaft which bears against a similar roller 60 on this link. Both links may be slotted at their lower ends and embrace the driving-shaft, as shown, for the purpose of guiding those ends.

Evidently the character of the resultant oscillation imparted to the work-holder and its contained blank is dependent upon the configuration of the cam-like actuators 56 and 59 and they may be so made as to give a desired oscillatory motion to the blank.

Referring now to Figs. 12, 13, and 14, which represent in a diagrammatic way the motions of the pivotal portions about which the blank-holder and its supports swing it will be noticed that the arc of oscillation $c-v$ of the lower edge of the blank is very considerably longer than the corresponding arc measured by the distance between z and z' of the upper edge. This is preferably so to effect a rolling of the surplus material on the edge of the blank sidewise of the latter without injury to the material within the die cavity which is being wrought to shape. If, now, the excursion of the lower edge is performed in substantially the same time as that of the upper, but in the opposite direction, the resultant motion for small angles of oscillation will be that of an oscillation about a substantially fixed axis lying between the two axes and whose nearness to the upper main axis depends upon the relative lengths of the two paths traced by the oppositely moving edges of the blank. If, however, the motion is in the same direction and the two edges reach their limit of motion at substantially the same time, the motion will simulate that of oscillation about an axis located outside or beyond the pivots. On the other hand if both edges move at the same time and through the same distance in the same direction the motion will be that of simple translation alternating first in one direction and then in the opposite. By altering the relative lengths of the arcs of oscillation while a type is being made, the resultant axis may be caused to move if desired toward the face of the forming type. By varying the conditions, that is, the time, the relative direction of the motion, and the configurations of the shifting cams, any desired character of oscillatory movement within certain limits, can be obtained as more fully set out in a companion application, but according to the preferred mode of operation the resulting oscillatory movement will be such as to effect a slight to-and-fro movement of the upper edge of the blank suffi-

cient to cause the area or surface of greatest work to be shifted and alternated from side to side of the mass within the die.

Referring now to the means for effecting a longitudinal movement of the blank-holder to bring successive portions of the blank therein under the die-carrier, any device suitable for the purpose may be employed, the construction herein shown being adapted for the purpose and embodying a feed-screw 61 mounted to rotate in bearings extending from the bed-plate B, and engaging with a nut 62 between end flanges 62', 62'' of which there is located a split sleeve 63 having a projection extending upward and engaging with the carriage G. This construction enables the nut to be clamped to the carriage, in which event, if the feed-screw is rotated, the carriage will be traversed in its guides while if the split-sleeve is unclamped, the carriage may be traversed to and fro by hand, a screw 63' being provided, as shown, for clamping the sleeve of the nut.

Motion is imparted to the feed-screw 61 from the main driving-shaft under the control, as respects the extent of such movement, of the shaft 2 of the die-carrier as organized in the present case. The device herein provided allows a variation in the feeding movement, it being evident upon reflection that some types being wider than others require a different amount of feeding movement to be imparted to the blank. The present device consists of a feed-wheel 63' secured to the shaft 2 and provided with peripheral portions whose relative radial depths correspond with and serve to control the amount of the rotation of the feed-screw 61 for each selected type-die. Mounted in a bearing 64 on the frame 4' is a slide-bar 65, a cross-pin 65' extending from which engages with the feed-wheel 63' and is depressed thereby varying amounts against the tension of a spring 66. Adapted to cooperate with this slide-bar 65 is a pawl 67 pivoted to the pawl-carrier in the form of a rock-arm 67' mounted to turn upon the feed-screw shaft 68, and adapted to engage with a ratchet-wheel 69 secured to that shaft. The lower end of the slide-bar is pivoted to a lug 70' extending from a pawl-lifter rock-arm 70 rotatably mounted upon the feed-screw shaft and which is provided with a lateral projection 71, adapted to engage with the pawl and disengage the same from the teeth of the ratchet-wheel. That is to say, for any given position of the slide-bar there will be a correspondingly definite position of the pawl-lifter 71, which therefore controls the movement and the engagement of the pawl with the teeth of the ratchet-wheel, as the pawl-carrier rotates and the pawl rides over the pawl-lifter. Hence the point at which the pawl engages with the ratchet-wheel will depend upon the

105

110

115

120

125

130

135

5 extent to which the pawl-lifter rock-arm has been rotated by the slide-bar 65, that is, it will be controlled by the position of the latter, which, in turn, is controlled in its position by the particular depression in the feed-wheel with which its cross-pin 65' engages, and which corresponds to the die brought to the type-forming point. As the amount of rotary movement given to the pawl-carrier is the same for every rotation of the main driving-shaft it is evident, therefore, that the amount of rotation given to the ratchet-wheel and the feed-screw shaft to which it is secured, will depend upon the 15 position of the pawl-lifter.

10 The actuator for actuating the pawl-carrier consists in the present instance of a link 72 pivoted to the pawl-carrier, and provided with a cam or antifriction-roller 72' which 20 contacts with a cam 73 secured to the main driving-shaft, a reaction spring 74 to maintain this contact being provided, while the end of the link is shown bifurcated and embracing the driving-shaft operating thus to 25 guide the movement of the link.

20 A machine organized and constructed according to the foregoing operates substantially in the following manner:—Assuming that a blank has been clamped in a blank-holder, and that the die-carrier C has been 30 adjusted to bring a particular die to the type-forming point, the pin 65' on the slide-bar 65 will assume a definite position with relation to the axis of shaft 2, and cause the 35 pawl-lifter or projection 71 to raise the pawl 67 out of engagement with the teeth of the ratchet-wheel, holding the same in a definite position. When the lever L is pulled back to release the clutch and effect therethrough 40 the rotation of the main driving-shaft from the rotating driving-pulley S', the cam 73 operates to shift the link 72 and cause the swinging of the pawl-carrier. The pawl now rides over the pawl-lifter ultimately 45 engaging with a tooth of the ratchet-wheel and turning the feed-screw shaft a particular amount depending upon the position of the pawl-lifter. The carriage G is thus shifted forward a definite amount.

50 Upon the continued rotation of the main driving-shaft the cam 21 next comes into action causing, through the connecting mechanism and the pinions 19 and 19' the movement of the work-holder toward the die and the engagement of the contained blank with the die. The oscillatory movement about the two axes will begin, in the preferred method of operation, some time after the die begins to advance into the 55 blank through the action of the described cams.

60 The material rolled from the edge of the blank and beyond the sides thereof during the oscillatory and transverse feeding movement of the blank, may be removed by any 65

suitable means after the types have been formed upon the blank, this constituting no feature of the present invention. Just before the completion of the full rotation of the main driving-shaft, arm 28 engaging with the inclined portion 35 of the locking lever is withdrawn from contact with pin 26 and the main driving-shaft ceases its movement.

Having described my invention, I claim:— 75

1. A blank holder, a support therefor pivotally connected thereto, and mechanism for imparting a to-and-fro working movement to the support when the blank in the holder is in contact with the forming tool. 80

2. A pivotally supported blank holder combined with a support therefor, and mechanism for imparting a to-and-fro working movement to said blank holder about its pivotal axis when the blank in the holder is in contact with the forming tool and for also imparting a to-and-fro movement to said support concurrently with the said movement of the blank holder. 85

3. The combination of a die; an oscillatory blank-holder; means for imparting a to-and-fro working movement to the holder independent of its said movement of oscillation; and means for causing a feeding movement of the die and a blank in the 95 blank-holder toward each other. 90

4. The combination of a die; an oscillatory blank-holder; means for imparting a to-and-fro working movement to the holder independent of its said movement of oscillation and with an amplitude decreasing in the later stages of the operation of the die; and means for causing a feeding movement of the die and a blank in the blank-holder 100 toward each other. 105

5. The combination of an oscillatory blank-holder, supports by which said holder is carried, an oscillator for oscillating the holder, and an oscillator for oscillating the supports. 110

6. The combination of an oscillatory blank-holder, supports by which such carrier is carried, an oscillator for oscillating the holder, an oscillator for oscillating the supports, and means for causing a relative feeding movement of the die and the blank-holder 115 toward each other. 110

7. The combination with a number of adjustable dies, of an oscillatory blank-holder, supports by which said holder is carried, an oscillator for oscillating the holder, an oscillator for oscillating the supports, and means for causing a relative feeding movement of the die and the blank-holder toward each other. 120

8. The combination of a number of adjustable dies, an angularly adjustable carrier upon which said dies are supported, an oscillatory blank-holder, supports by which said holder is carried, an oscillator for os- 125 13

cillating the holder, an oscillator for oscillating the supports, and means for causing a relative feeding movement of the die and the blank-holder toward each other.

5 9. In a typebar-machine, a blank-holder having two axes of oscillation, combined with means for oscillating the holder about both axes with an amplitude decreasing in the later stages of the type-forming operation.

10 10. The combination with a blank-holder, and means for feeding the same longitudinally, of an oscillator for imparting an oscillatory movement to the holder in all its 15 longitudinal positions.

11. The combination of a blank-holder, oscillatory supports by which said holder is carried, and means for feeding a die and the holder toward each other in any longitudinal position which the holder may 20 assume.

12. The combination, of a blank-holder supported for oscillatory movement about two independent axes, oscillators for oscillating the blank-holder, means for feeding the blank-holder and a die toward each other, means for imparting a longitudinal movement to the blank-holder, and actuators for varying the throw of the oscillators.

30 13. The combination with a blank-holder, of a die-carrier; a feed-wheel movable with the carrier and having a peripheral portion of varying depths; an actuator for imparting a longitudinal movement to the holder; 35 and mechanism intermediate said feed-wheel and said actuator for controlling the amount of such movement comprising a member having a fixed amount of movement, and a member engageable with the 40 first-mentioned member at different points in the path of movement of the latter.

14. The combination with a die-wheel, of a blank-holder oscillatory about two axes, means for imparting a longitudinal motion 45 to the holder embodying a ratchet-wheel, a feed-wheel and means interposed between said feed-wheel and said ratchet-wheel for varying the movement imparted to the latter.

50 15. The combination, of a feed-wheel provided with a peripheral portion of varying depth, a ratchet and pawl mechanism, and a pawl-lifter for determining the engagement of the pawl with the ratchet-wheel, 55 and the rotation of the ratchet-wheel.

16. The combination, of a plurality of oscillators, provided with members adapted to move toward and away from the axes of oscillation, and means for controlling 60 such to-and-fro movements during the actuation of the oscillators.

17. The combination, of a die-carrier, means for locking the same in an adjusted position, a feed-wheel moving with the said

carrier, and a slide bar contacting with the 65 operative portion of said feed wheel.

18. The combination with a blank holder, of a support on which said holder is pivotally mounted, means for oscillating said holder about its pivotal axis and for also 70 oscillating said support, slides upon which said support is carried, and means for shifting the slides to-and-fro.

19. The combination with a blank holder, of a support on which said holder is pivotally mounted, means for oscillating said holder about its pivotal axis and for also 75 oscillating said support, slides upon which said support is carried, means for shifting the slides to-and-fro, and a carriage shiftable 80 longitudinally of the blank and upon which said slides are mounted.

20. The combination with a blank holder, of a support on which said holder is pivotally mounted, means for oscillating said 85 holder about its pivotal axis and for also oscillating said support, slides upon which said support is carried, a carriage shiftable longitudinally of the blank and upon which said slides are mounted, wedge-bars movable 90 transversely of the slides and engaging therewith, and wedge-bar actuating means.

21. The combination with a blank holder, of opposed supports on which said holder is pivotally mounted, means for oscillating 95 said holder about its pivotal axis and for also oscillating said supports, a carriage shiftable longitudinally of the blank, slides mounted on said carriage and by which said supports are carried, a wedge-bar engaging 100 with each slide and provided with a rack, pinions engaging with said racks, a spring-returned pinion shaft, a cam for rotating the pinion shaft, and intermediate mechanism for transmitting motion from the cam to the 105 pinion shaft whatever be the position of the carriage.

22. The combination with a blank holder, of opposed supports on which said holder is pivotally mounted, means for oscillating 110 said holder about its pivotal axis and for also oscillating said supports, a carriage shiftable longitudinally of the blank, slides mounted on said carriage and by which said supports are carried, a wedge-bar engaging 115 with each slide and provided with a rack, pinions engaging with said racks, a spring-returned pinion shaft to which said pinions are secured and which is longitudinally shiftable with the carriage, a cam for rotating the pinion shaft, and intermediate mechanism 120 for transmitting motion from the cam to the pinion shaft and with relation to which said pinion shaft is longitudinally shiftable.

23. The combination with a settable die carrier, of a feed controller movable in unison therewith, a shiftable blank holder, a

cam, and mechanism intermediate the cam and the feed controller for shifting the blank holder a distance determined by the set position of the feed controller and in consonance with the line space value of the selected die.

24. The combination with a settable die carrier, of a feed controller movable in unison therewith, a shiftable blank holder, means comprising a pawl and ratchet mechanism for shifting the blank holder, mechanism intermediate the feed controller and the pawl of the pawl and ratchet mechanism for setting the pawl to correspond with the set position of the feed controller, and a cam for actuating the pawl and thereby shifting the blank holder in consonance with the line space value of the selected die.

25. The combination with a settable die carrier, of a feed controller movable in unison therewith, a shiftable blank holder, means comprising a pawl and ratchet mechanism for shifting the blank holder, mechanism comprising a pawl lifter intermediate the feed controller and the pawl of the pawl and ratchet mechanism for lifting the pawl a distance to correspond with the set position of the feed controller, and a cam for actuating the pawl and thereby shifting the blank holder in consonance with the line space value of the selected die.

26. The combination with a support mounted for oscillatory movement, of a blank holder mounted on the support, and an oscillator having a variable cam-controlled throw for oscillating said support.

27. The combination with a support mounted for oscillatory movement, of a longitudinally shiftable carriage on which the support is mounted, a blank holder mounted on the support, and an oscillator engaging with said support throughout the longitudinal movement of the carriage and having a variable cam-controlled throw for oscillating the support.

28. The combination with a support mounted for oscillatory movement, of a longitudinally shiftable carriage on which the support is mounted, a blank holder oscillatably mounted on the support, an oscillator engaging with said support throughout the longitudinal movement of the carriage and having a variable cam-controlled throw for oscillating the support, and a second oscillator for oscillating the blank holder relatively to its said support.

29. The combination with a settable die carrier, of a longitudinally shiftable carriage, feed mechanism for controlling the intermittent longitudinal movement thereof in consonance with the line space values of the selected dies, a support mounted on said carriage for oscillatory movement, means for shifting said support toward and away from the die carrier, a blank holder mounted on

said support for oscillatory movement, an oscillator having a variable cam-controlled throw and comprising an elongated bar engaging with said support for oscillating the same, and a second oscillator also having a variable cam-controlled throw and comprising a vibrating link engaging with said blank holder throughout the longitudinal movement of the carriage for oscillating the blank holder relatively to its said support. 70

30. A blank holder pivotally connected with a support, said support, a mechanism for imparting an oscillatory to and fro working movement to the support and to the holder when the blank in the holder is in contact with the forming tool. 75

31. The combination with a support mounted for oscillatory movement, of a blank holder mounted on the support, and an oscillator having a variable stroke for oscillating said support. 80

32. A blank holder having an axis parallel with each edge of the blank, and means for concurrently oscillating the holder upon each of such axes. 85

33. The combination with a blank holder having pivots constituting an axis adjacent to one edge of the blank, a holder in which said pivots are mounted, an axis for said holder adjacent to the other edge of the blank, rock shafts for oscillating the holder upon each of said axes and connected thereto respectively by links, a slideway, a slide upon each of the rock shafts and connected to the respective links, and independent means for shifting said slides to vary the oscillations, means to feed the blank holder and comprising a screw, a ratchet wheel thereon, a pawl, means for giving the pawl a uniform stroke, means for controlling the working portion of such stroke and comprising a cam wheel, a slide bar controlled thereby, the periphery of said cam wheel having depressions of varying depths varying according to the width of the respective types, 105 and means for advancing the blank holder toward the working position and comprising wedge members engaging the same, and a spring returned pinion for controlling said wedges by engagement with a rack thereon. 110

34. A blank-holder combined with a support therefor, of mechanism for imparting the resultant of a compound working movement to the support when the blank in the holder is in contact with the forming tool. 115

35. A pivotally supported blank-holder combined with a support therefor, of mechanism for oscillating said blank-holder about its pivotal axes when the blank in the holder is in contact with the forming tool and for also imparting an oscillation to said support concurrently with the said movement of the said blank-holder. 125

36. The combination with a blank-holder, of a support on which said holder is pivot- 130

ally mounted, means for oscillating said holder upon said axes and for also oscillating said support, means for carrying said support, and means for shifting said carrying means.

37. The combination with a support, of a blank-holder pivoted to the support, an oscillator having a variable stroke for oscillating said support, an oscillator for oscillating the blank-holder, a blank-holder having two parallel axes, and means for concurrently actuating said oscillators for oscillating the holder upon each of said axes.

38. The combination with a support, of a blank-holder pivoted thereto, and means for independently oscillating the blank-holder and the support.

39. The combination with a blank-holder, of a support to which the blank-holder is pivoted, and individual oscillators for the blank-holder and the support.

40. The combination with a blank-holder, of means for feeding the same longitudinally, and means for oscillating said blank-holder upon each of two axes parallel to the direction of feed.

41. The combination with a support mounted for oscillatory movement, of a blank-holder mounted on the support for oscillatory movement, an oscillator for oscillating the same, and means for severally varying the strokes of said oscillators.

42. The combination with a blank-holder pivotally mounted upon two parallel axes, means for oscillating the same upon each of said axes, and means for varying the length of the excursions of the oscillations.

43. A blank-holder having an axis parallel with each edge of the blank, means for concurrently oscillating the holder upon each of such axes, and means for independently varying the oscillation upon each of said axes.

44. The combination with a blank-holder, a support to which the blank-holder is pivoted, a carriage to which the support is pivoted, means for shifting the carriage longitudinally in a direction parallel with the pivotal axes of said members, means for oscillating each of the same upon its pivot, and individual means for varying the length of said oscillation.

45. The combination with a blank-holder pivotally mounted upon a support, and means for oscillating the blank holder and the support.

46. The combination with a blank-holder, and means for shifting the same with the resultant of an oscillation about two axes.

47. The combination with a blank holder, and means for feeding the same longitudinally, of an oscillator for imparting oscillatory movement to the holder while at various longitudinal positions.

48. The combination of a blank holder, oscillatory supports by which said holder is carried, and means for feeding a die and the holder one toward the other while the holder is at any one of a number of positions of adjustment.

49. A blank holder having a pair of axes each parallel with the edge of the blank, and means for concurrently oscillating the holder upon both of such axes.

50. The combination with a pivotally mounted support, of a blank holder pivotally mounted upon said support, an oscillator and means for varying its stroke from zero for oscillating said support, an oscillator and means for varying its stroke from zero for oscillating said blank holder, and means for actuating said oscillators.
